CORN HUSKER

William T. Bond, Richmond, Ind.

Application November 13, 1946, Serial No. 709,594

3 Claims. (Cl. 130—5)

1

My invention relates to corn pickers of a generally known type which is adapted to be drawn along the rows of standing corn to gather, husk and deliver the husked corn to a carrier.

In one form of husking unit generally in use, the ears of corn to be husked are fed from a hopper onto a plurality of rubber and steel rolls mounted in contacting position and adapted to be rotated in opposite directions to grab and strip the husk from the ear. In this form the surface of the rubber rolls is above that of the iron rolls and the rotational movement of all of the rubber rolls is in the same direction to produce a lateral force always working to move the contents of the husking bed toward one side of it, with the result that the material may become piled up against one side of the bed. When this occurs, the husking rollers adjacent that side of the bed become choked, resulting in rapid deterioration of the husking rolls and an inefficient husking operation.

It is the main object of my invention to prevent the pile up of the material on one side of the husking bed and to bring about a distribution of the material in the husking bed which will insure a rapid, clean and efficient operation of the husking mechanism with the least wear and tear on the apparatus.

In accordance with this subject, I provide a feeding and distributing mechanism adapted to be mounted in the husking bed, and operating to position the corn in parallel alignment with the husking rolls, and at the same time tend to move it laterally of the bed in opposition to the lateral moving force exerted by the rubber husking rolls.

In its preferred form, the feeding and distributing mechanism comprises a plurality of rotating spiral blades mounted transversely of the husking bed above and at right angles to the husking rolls, and in such position that as the spiral blades are rotated, their advance faces will engage the corn to move it across the faces of the husking rolls while at the same time imparting a rotational force to the ears.

As a further feature of this invention, the outer edges of the spiral blades may be equipped with protective means which will prevent abrasion or other injury to the outer covering of the kernels which would make them unacceptable as seed corn.

Other features and advantages of the invention will be apparent from the following description read in connection with the drawings.

In the drawings illustrating this invention:

2

Fig. 1 is a general view of a corn picker to which my invention may be applied.

Fig. 2 is a side elevation of the mechanism embodying the features of my invention.

Fig. 3 is a top plan view of the mechanism of Fig. 2.

Fig. 4 is a perspective view of a husking bed and mechanism of the invention.

Fig. 5 is a fragmentary plan view of the husking rollers, and Fig. 6 is a cross-sectional view of the husking rollers.

Except for the feed mechanism illustrated, the corn picker shown in Fig. 1 is a conventional and commercial form of picker in which pick up noses 10 and 11, housing a plurality of picker chains, not shown, gather and feed the corn stalks onto snap rollers which snap the corn ears from the stalks and feed them onto a conveyor mechanism 12, which lifts them into a hopper 13, from which they are fed into a husking unit 14. The lower end of the husking bed opens into a hopper 15 at the lower end of a conveyor 16 which conveys the corn to a carrier attached to the picker.

Included in the husking unit 14 as a part of the standard equipment of the picker illustrated, are three iron rolls 17, 17, 17 and three rubber rolls 18, 18, 18 in alternate relation so that one rubber roll and one iron roll form a pair of husking rolls. The planes of the upper surfaces of the rubber rollers 18, 18, 18 are slightly above the planes of the steel rollers 17, 17, 17, so that the movement given to the ears of corn in the husking bed as a result of the rotation of these rollers will be in the direction of rotation of the rubber rollers, which is clockwise as viewed from the lower or discharge end of the husking bed. Alternate rolls are positively driven in opposite direction with respect to each other. The husking rolls 17, 17, 17 and 18, 18, 18 are located in a sheet metal housing, including parallel side members 20 and 21, which are stiffened along their upper edges by means of iron angles 22 and 23.

The feed mechanism of this invention for keeping the ears uniformly distributed over the husk bed includes a plurality of spiral blades 25, 26 and 27, mounted upon rotating shafts 28, 29 and 30, respectively, and extending transversely of the husking rolls. The shaft 28 is rotatably supported in adjustable bearing brackets, such as shown at 31, secured to the side member 20, by a bolt 32, extending through a slot 33, in the bearing bracket 31 and the side member 20.

The shafts 29 and 30 are rotatably supported

between frame plates 35 and 36 having their ends adjacent the receiving end of the husking unit journaled upon the shaft 28. Secured to the ends of the frame plates 35 and 36 adjacent the discharge end of the husking unit is an inverted U-shaped tie member comprising side members 38 and a top member 40. The side members 38 are provided with slots 41 to receive a clamping bolt 43 for an adjustable angle stop 44 adapted to rest upon the upper edge of the side member 20 and 21 for supporting the lower end of the frame and for permitting the adjustment of the vertical distance between the feeding mechanism and the adjacent ends of the husking rolls.

Since the supporting frame for the spiral feed member is pivoted on the main shaft 28, the lower end of this frame is free to rise and fall within the limits of the stops 44, and the mechanism will accommodate itself to different size ears with but little attention.

The right-hand ends of the shafts 28, 29 and 30, looking toward the delivery end of the husking unit, are extended outwardly beyond the side member 21 of the metal housing, the shaft 28, through the adjustable bearing bracket 31, the shafts 29 and 30, through slots 50 and 51, provided in the side member 21, and opening through the upper edge thereof.

Secured to the outer end of shaft 28 is a cogwheel 52, chain driven from the main drive mechanism of the picker. Also mounted upon the shaft 28, between the cogwheel 52 and the side member 21, is a cogwheel 53, chain connected with the cogwheel 54, on shaft 29. A second cogwheel 55, on shaft 29, is chain connected with a cogwheel 56, on shaft 30. By this driving arrangement, the three shafts 28, 29 and 30 will be positively driven in a clockwise direction.

The bearings for the shafts 29 and 30 are adjustably secured to the frame plates 35 and 36 by means of bolts 60 extending through slots in said frame members 35 and 36. The frame member 36 is also provided with slots for the shafts 29 and 30. This construction provides for adjustment of the shafts 29 and 30 longitudinally of the frame plates 35 and 36 for tensioning of the drive chains.

The side member 21 is reinforced and braced adjacent the edges of the slotted portions 50 and 51 by U-shaped members 64 and 65 fastened to the outer face of the side member 21.

It is especially important in the husking of corn which is to be used for seed that abrasions to the outside covering of the corn kernel be avoided. Since such abrasions might be produced by sharp corners or edges of the spiral blades 25, 26 and 27 striking the kernels, the following provisions are made for avoiding such injury.

Secured to the periphery of the spiral blade 25 and covering the advance corner thereof, is a circular rod 68 which may be welded to the outer edge of the blade. Since the blade 25 is the first to engage the corn as it enters the husking bed, the work required of it is greater than that required by the other two blades 26 and 27, and, consequently, it must have a greater stiffness than the latter blades.

The work surface for each of the blades 26 and 27 may be provided by tabs or extensions 70, 70 of material having substantially the same degree of flexibility as four or five ply rubber belting. These tabs 70, 70 are secured to spiral blades 26 and 27 at closely spaced intervals and extend outwardly therefrom as extensions of the spiral

blades. A single one of the tabs 70 may be attached to the blade 25 near its forward end to assist in moving the corn away from the adjacent side of the husking bed.

To appreciate the advantages of my feed mechanism, it is here pointed out that the rubber rolls 18, 18, 18 are rotating to the right, or clockwise, while the iron rolls 17, 17, 17 which, located below the upper surfaces of the rubber rolls, are rotating to the left, or anti-clockwise. Since the rubber rolls afford the frictional contact with the corn, the tendency will be for the corn in the husk unit to be moved transversely across the bed toward the right-hand side. As a matter of experience, it has been found that in those husk units, when the corn is moved into engagement with the husking rolls, the corn is actually piled up on the right-hand side of the husking bed to choke the rolls at that side of the bed which greatly shortens the life of this pair of rolls, and results in a very inefficient husking operation.

In the operation of the mechanism of my invention, the spiral blades 25, 26 and 27 are rotating to the right, or clockwise as viewed in Figure 2, and the advancing faces of these spiral blades will engage the corn to produce a moving force toward the left side of the husking bed and against the force of the rubber rolls tending to move the ears of corn toward the right side of the bed. These opposing forces will tend to swing the ears into parallelism with the husking rolls and to impart to the ears a rotary motion which will insure a complete stripping of the husk from the ear. As is readily apparent from examination of Figures 2 and 3, the direction of movement of the bottom portions of each of the spiral blades 25, 26 and 27 is in the direction to produce a downward movement of the corn along the husking bed in addition to the lateral component of movement imparted to the corn in the manner described above.

The right-hand ends of the spiral blades are terminated as closely as possible to the right-hand side of the husking bed, while the left-hand ends of the blades may be terminated at a distance from the left-hand side of the bed approximately half the width of the rubber roll adjacent that side. Thus, while the force of the spiral members which is exerted upon the corn transversely of the husking bed and toward the left-hand side is greater than that exerted in the opposite direction by the rubber rolls, such force is not exerted beyond the center line of the rubber roll at the left-hand side of the husking bed, and since the rotation of this roll is away from the adjacent side of the bed, there can be no piling up or choking at the rollers located at this side of the bed.

Experiments have demonstrated that an equipment embodying the features of my invention not only saves wear and tear on the parts, but it results in a cleaner and more efficient husking operation with less injury to the surfaces of the kernels than in other equipment known to me.

Although I have shown and described my invention with respect to certain details of construction, I wish it to be understood that I am not to be too closely limited thereto, many modifications being possible without departing from the spirit or scope of my invention.

I claim:

1. In a corn husking device, a plurality of sets of husking rolls disposed in parallel side by side relationship to define a husking bed free of obstructions to lateral movement of the corn ears thereon, each set comprising a rubber roll having

a spiralled surface and a cooperating metal roll, means for rotating all of said rubber rolls in one direction and all of said metal rolls in the opposite direction, the top surfaces of said rubber rolls being elevated above the top surfaces of said metal rolls, whereby the corn ears tend to be laterally displaced toward one side of the husking bed and a plurality of feeding elements mounted for rotation transversely of and above said husking bed, said feeding elements having helical surfaces formed on their peripheries and adapted to engage the corn ears on the husking bed, and means for rotating said feeding elements in the direction to cause all of said helical surfaces to urge the corn ears laterally in the same direction in opposition to the lateral forces exerted by said rubber husking rolls and longitudinally toward the discharge end of the husking bed.

2. In a corn husking device, a plurality of sets of husking rolls disposed in parallel side by side relationship to define a husking bed free of obstructions to lateral movement of the corn ears thereon, each set comprising a rubber roll having a spiralled surface and a cooperating metal roll, means for rotating all of said rubber rolls in one direction and all of said metal rolls in the opposite direction, the top surfaces of said rubber rolls being elevated above the top surfaces of said metal rolls, whereby the corn ears tend to be laterally displaced toward one side of the husking bed, and a plurality of augering members rotatably mounted transversely of the bed above the husking rolls and adapted to engage the corn ears on the bed, and means for rotating all of said augering members in the same direction to oppose the lateral forces imparted to the corn ears by the rubber husking rolls.

3. In a corn husking device, a plurality of sets of husking rolls disposed in parallel, side by side relationship to define a husking bed free of obstructions to lateral movement of the corn ears

thereon, each set comprising a rubber roll and a cooperating metal roll, means for rotating all of said rubber rolls in one direction and all of said metal rolls in the opposite direction, the top surfaces of said rubber rolls being elevated above the top surfaces of said metal rolls, whereby the corn ears tend to be laterally displaced toward one side of the husking bed, and a plurality of feeding elements mounted for rotation transversely of and above said husking bed, said feeding elements each comprising a helical metal blade having outwardly projecting flexible tabs secured to the helical edge thereof and adapted to engage the corn ears on the bed, and means for rotating said feeding elements in the direction to cause said tabs to move the corn ears laterally in the same direction in opposition to the forces imparted to the corn ears by the rubber husking rolls and longitudinally in the direction of the discharge end of the husking bed.
